WRINGER

Earl V. Godfrey, Girard Township, Erie County, Pa., assignor to Lovell Manufacturing Company, Erie, Pa., a corporation of Pennsylvania

Application May 10, 1930, Serial No. 451,436
Renewed July 9, 1932

2 Claims. (Cl. 68—32)

Power driven clothes wringers present difficulty as to the safety of the operator. Efforts have been made to minimize this by providing such wringers with release devices by means of which the pressure on the rolls may be instantly released in order to minimize the injury to the hands of an operator caught between the rolls. Devices have also been provided for shutting off the driving mechanism so as to prevent the continued turning of the rolls as this may cause injury even though the pressure is released through the abrasive action of the rolls. The present invention is designed to improve such devices, particularly the devices for controlling the driving mechanism, and in the preferred form having special reference to the relation of such controlling mechanism and release device. Features and details of the invention will appear from the specification and claims.

A preferred embodiment of the invention is illustrated in the accompanying drawing as follows:—

Fig. 1 shows a front elevation of a wringer with the power mechanism therefor shown in outline.

Fig. 2 an end view of the wringer showing the switch mechanism.

Fig. 3 a section on the line 3—3 in Fig. 1.

Fig. 4 a section on the line 4—4 in Fig. 1 viewed toward the top.

Fig. 5 a section on the line 5—5 in Fig. 2.

The wringer frame has a base 1 and side stiles 2. Rolls 3 and 4 are mounted in the frame in the usual manner. A spring 5 exerts pressure on the rolls. A top bar 6 extends across the side stiles.

The release device comprises a sleeve 7 which extends through an opening 8 in the top bar. The opening 8 has extending slots 9. The sleeve 7 is provided with locking shoulders 10 which are adapted to pass through the slots 9 when turned in register therewith. The shoulders operate in connection with cams 11 at the edges of the opening 8 on the under-side of the top bar 6. Handles 12 are arranged on the sleeve and when the shoulders 10 are on the cams 11 with pressure on the spring 5 the handle 12 extends parallel to the top bar of the wringer. A screw 12a extends through the sleeve by means of which the tension on the spring may be adjusted.

Safety bars 13 are arranged at the front and rear of the wringer adjacent to the top bar. These are pivoted on cross plates 14 arranged on the stiles 2 by means of pins 15.

A snap switch 16 comprises contact plates 17 which are connected with posts 18 from which wires 18a extend to a motor 19. This snap switch

is of ordinary construction. It has a U-shaped bridge plate 20 pivoted on pins 21. A reversing pin 22 is pivotally mounted by means of a pin 23 on a slide 24. The pin 22 extends through an opening 25 in the bridge plate and a spring 26 is tensioned between the bridge plate and the base of the pin 22. Push pins 27 and 28 extend from the slide 24. As the pin 28 is depressed the slide 24 is moved so as to carry the pivot 23 beyond the pivot 21 and the tensioning of the spring snaps the bridge plate out of engagement with the contacts. A reverse movement snaps the bridge plate into contact.

The safety bars have extensions 29 which project over the pin 28 so that as either safety bar is moved inwardly the inner end of the extension 29 moves downwardly thus operating the pin 28 to open the switch. Likewise extensions 30 at the lower end of the safety bars extend under the pin 27 and with an upward movement of the safety bars are moved upwardly so as to re-set the switch.

The wringer may be provided with any convenient connecting mechanism between the motor and the drive roll. As shown the drive roll has a beveled gear 32 meshing with a beveled gear 33. The beveled gear 33 is mounted on a shaft 34 which carries a beveled gear 35. A beveled gear 36 meshes with the beveled gear 35 and is mounted on a shaft 36a. A gear 37 is mounted on the shaft 36a and meshes with a pinion 38 carried by a driving shaft 39 of the motor.

It will be noted that the safety bars extend along the top of the wringer in position to be actuated by an operator. It will be understood that an operator caught by the rolls usually acts somewhat as in a panic and the instinctive thing to do is to hit at the safety bar so that the inward movement is of importance in assuring this movement. Further the handle of the safety release is adjacent to the safety bar so that with the same movement the handle of the safety release may be actuated and by a movement of the hand of the operator in the same direction as the safety bar. The bar should be near enough the top of the wringer so that the upper part of the hand of the operator extends somewhat over the top of the top bar. Thus the operator instinctively thrusting the hand forward can operate the top bar without undue interference from the face of the wringer. The instinctive act of the operator also ordinarily reaches for the wringer in a manner to resist the impulling of the caught hand and here again the position of the bail so as to intercept the hand as being placed

forward toward the frame for this purpose is desirable. It is also very desirable that the bite of the wringer shall be clearly and completely visible to the operator standing in the normal position for feeding the wringer. The critical point of observation for the operator is the bite itself and if this view is obstructed the danger of catching the hand is increased. With the present device and with the top bar extending above the roll this visibility is not obstructed and consequently the operator can with greater safety operate the wringer. It will be noted that the rendering inoperative of the power means, or the pressure exerting means will, to a large extent, prevent further injury to an operator caught in the rolls. While I have shown the safety bars as operating a safety device by rendering inoperative the power driven means I do not wish to be understood as limited in the broader phases of my invention to the particular safety device which may be operated through safety bars located and operating as in applicant's structure.

What I claim as new is:—

1. In a wringer, the combination of a frame comprising a top bar; rolls in the frame; a power

driving means for the rolls; means putting pressure on the rolls; a release device for releasing pressure on the rolls; a handle on the release device extending along the top bar; and devices rendering the power-driving means inoperative comprising a bar extending across the wringer frame adjacent to the handle of the release device and operable with the handle by a single one-way movement of a hand of an operator.

2. In a wringer, the combination of a frame comprising a top bar; rolls in the frame; a power driving means for the rolls; means for putting pressure on the rolls; a release device for releasing pressure on the rolls; a handle on the release device extending along the top bar; and devices rendering the power-driving means inoperative comprising a bar extending across the wringer frame adjacent to the handle of the release device and operative with a movement in the same direction as the movement of the handle in actuating the release device whereby the bar is operable with the handle by a single one-way movement of a hand of an operator.

EARL V. GODFREY. 25
